PATENTED NOV. 5, 1907.

J. STRANG.

DIAL FOR WATCHES AND CLOCKS.

APPLICATION FILED OCT. 26, 1905.

UNITED STATES PATENT OFFICE.

JOHN STRANG, OF QUEBEC, QUEBEC, CANADA.

DIAL FOR WATCHES AND CLOCKS.

No. 870,481.

Specification of Letters Patent.

Patented Nov. 5, 1907.

Application filed October 26, 1906. Serial No. 284,521.

To all whom it may concern:

Be it known that JOHN STRANG, a subject of the King of Great Britain, residing at Quebec city, Province of Quebec, Dominion of Canada, has invented 5 new and useful Dials for Watches and Clocks, of which the following is a specification.

The invention relates to improvements in dials for watches and clocks.

The object of the present invention is to improve 10 the construction of dials for watches and clocks, and to provide an exceedingly simple and inexpensive dial adapted to enable the time in minutes and hours to be ascertained at night or any other time without striking a light.

15 A further object of the invention is to provide a watch dial of this character, which will enable the hours and minutes to be ascertained even by the blind without confusion and without interfering with the second hand of a watch.

20 With these and other objects in view, the invention consists in the construction and novel combination and arrangement of parts, hereinafter fully described, illustrated in the accompanying drawing and pointed out in the claims, hereto appended; it being understood 25 that various changes in the form, proportion, size, and minor details of construction, within the scope of the claims, may be resorted to without departing from the spirit or sacrificing any of the advantages of the invention.

30 In the drawing:—Figure 1 is a plan view of a watch, the lid being open. Fig. 2 is a side elevation partly in section. Fig. 3 is a perspective view of a portion of the dial showing the raised or embossed Arabic and Roman numerals. Fig. 4 is an enlarged detail sectional view, illustrating the manner of protecting the seconds hand.

Like numerals of reference designate corresponding parts in all the figures of the drawing.

1 designates a watch dial, having a solid central 40 portion and provided at its periphery with a circular series of Roman numerals 2 for use in connection with the minute hand 3 to determine the time in minutes, and the said dial is provided with an inner circle of Arabic numerals 4, arranged concentric with the outer 45 Roman numerals for use in connection with the hour hand 5 of the watch. Both the Roman and Arabic numerals are raised or embossed so as to be readily distinguished by the touch to tell the time at night or in the Arctic regions where the sun is invisible for 50 long periods of time. The inner Arabic numerals

correspond with the outer Roman numerals, and are arranged on the same radial lines, and in determining the time, the hour is first ascertained by finding the hour hand and its position with relation to the inner numerals. The time in minutes is then ascertained 55 by locating the minute hand and ascertaining its position with relation to the outer Roman numerals and by employing two sets of numerals of different character, all confusion in ascertaining the time is prevented. The frame or casing of the watch is also divided into quarters by projections 7 located opposite the 3, 6, 9 and 12, which are intended to mark the location of the hours indicated by such numbers, and thereby facilitate the finding of the numbers in their vicinity. The lid 8, which is preferably arranged to 60 swing to the right in opening, is provided with corresponding depressions 9, which receive the projections when the lid is closed. The lid is connected with the case by a hinge 10 of the ordinary construction.

65 In order to protect the seconds hand of the watch, the dial is provided with a depression 12, and a small crystal 13 is arranged over the seconds hand, so that the hand of the person using the watch and ascertaining the time by touch will not come in contact with 70 the seconds hand and interfere with the running of the watch.

The improvements herein shown and described do not necessitate any change in the movement of a watch or clock, or the arrangement of the hands thereof, and 80 it may be applied to any ordinary watch or clock, and it will enable the blind and others to readily ascertain the time in minutes and hours by the sense of touch.

Having thus fully described my invention, what I 85 claim as new, and desire to secure by Letters Patent, is:—

1. A dial for watches and clocks having inner and outer raised numerals arranged to correspond to the minute and hour hands of a watch or clock, said dial being also provided with a depressed portion to receive the seconds hand, and a small crystal fitted over the depressed portion to cover and protect the seconds hand.

90 2. A watch or clock, comprising a case divided into quarters by projecting lugs and having a hinged lid with indentations corresponding to and arranged to receive the projections when the lid is closed, and a dial having inner and outer raised numerals.

95 3. A dial for watches having inner and outer series of raised numerals arranged to correspond with the minute and hour hands of a watch, said dial being also provided with a depressed portion intersecting the inner series of numerals, projecting lugs located opposite the 9, 12 and 3

of the inner series of numerals, a seconds hand arranged in the depressed portion, a small crystal fitted over the depressed portion to protect the seconds hand, and hour and minute hands, the hour hand traveling over the inner numerals and the minute hand extending beyond the inner numerals and travelling over the outer numerals.

4. A dial for watches and clocks having inner raised Arabic numerals and outer raised Roman numerals arranged to correspond to the minute and hour hands of a 10 watch or clock, said dial being also provided with a de-

pressed portion to receive the seconds hand, and a small crystal fitted over the depressed portion to cover and protect the seconds hand.

In testimony, that I claim the foregoing as my own, I have hereto affixed my signature in the presence of two 15 witnesses.

JOHN STRANG.
